UNITED STATES PATENT OFFICE.

OSCAR F. GLIDDEN, OF GRAND RAPIDS, MICHIGAN.

REMOVABLE TANK FOR REFRIGERATORS.

SPECIFICATION forming part of Letters Patent No. 437,299, dated September 30, 1890.

Application filed December 21, 1889. Serial No. 334,587. (No model.)

To all whom it may concern:

Be it known that I, OSCAR F. GLIDDEN, a citizen of the United States, residing at Grand Rapids, in the county of Kent and State of Michigan, have invented certain new and useful Improvements in Removable Tanks for Refrigerators; and I do hereby declare the following to be a full, clear, and exact description of the invention, such as will enable others skilled in the art to which it appertains to make and use the same.

My invention relates to a removable tank for refrigerators; and it consists in providing a refrigerator with a tank of peculiar form adapted to be inserted in and easily removed, and having means of closing all external openings and preventing the passage of air into the refrigerator-chamber through the opening in the walls provided for the faucet of the tank; and the improvement consists in the construction, combination, and arrangement of the various parts and details herein-after described, and particularly pointed out in the claims, reference being had to the accompanying drawings, wherein—

Figure 1 is a perspective of a corner of an ordinary refrigerator, with parts in dotted outline, showing my tank in place; Fig. 2, vertical section of same, and Fig. 3 perspective of tank removed from its seat.

Like letters indicate like parts in each of the several figures.

A represents a rectangular tank provided with a faucet G and having secured to its front face a block C, having a face E, which is flush with the back of the chamber O', arranged in the vertical walls of the refrigerator O and having the front opening O'', which may be provided with an ornamental casing 40 surrounding the same, if desired. The bottom of the chamber is provided with a pan P, having an opening communicating with a drip-pipe K, which communicates with the drip-pipe K' of the refrigerator, and which 45 communicates with the chamber J, containing the tank.

The block C has shoulders F and D for engaging the sides of the opening in the vertical walls of the refrigerator to form a tight joint, as shown in Fig. 2, and the face D may be provided with a packing D', inserted between the shoulder and the inside of said

walls to make the joint air-tight, if desired.

The tank rests upon suitable supporting-bars L L', arranged across the bottom of the 55 tank-chamber, L' having a groove M, in which sets the rear edge of the tank A, to form a firm seat and prevent the tank from moving backward from the opening. This is also further guarded against by the cleat N, 60 secured across the back of the chamber and engaging the back of the tank. I I are handles. It is obvious that a rectangular tank having a block C for engaging the sides of the opening and a spout projecting from the 65 tank outward through such opening could not be removed from the chamber J without removing the spout. To provide for such removal, I make the rear side of the tank flaring from the bottom upward toward the top, 70 so that the distance across the bottom is considerably less than that across the top, as shown in Figs. 2 and 3 and indicated by B. I arrange the cleat N at such distance from the bottom as that when the tank being lifted 75 upward is disengaged from its seat M the cleat N and the end of the tank will be out of contact and the tank may then be drawn obliquely upward and lifted out of the chamber.

Having thus described my invention, what I 80 claim and desire patented is—

1. In combination with a refrigerator, a removable tank having a faucet arranged to communicate with the exterior of the refrigerator and having the distance across its top greater 85 than that across its bottom, substantially as and for the purposes set forth.

2. In combination with a refrigerator having a chamber, as J, provided with bars, as L L', and a cleat, as N, and a removable tank 90 having a flaring rear end, as B, substantially as and for the purpose set forth.

3. In combination with a refrigerator having a chamber, as J, provided with an opening through its vertical walls adapted to admit a faucet, and a removable tank having a faucet and provided with shoulders adjacent to the faucet adapted to engage the sides of said opening and form a substantially air-tight joint, substantially as described. 95

4. In combination with a refrigerator having a chamber, as J, provided with tank-supporting bars, as L L', and an opening through its vertical walls, a removable tank, as A, 100

having a beveled or flaring corner, as B, and a faucet, as G, and provided with a block, as C, for engaging the sides of the opening and forming a tight joint, substantially as set forth.

5. In combination with a refrigerator having a chamber, as J, provided with tank-supporting bar L and bar L', having the groove M and a cleat N and an opening through its vertical walls arranged substantially as described, a removable tank, as A, having a beveled or flaring rear lower corner, as B,

adapted to engage the groove M and provided with a block C, having faces E and shoulders F and D for engaging the sides of said opening, as set forth, and a faucet G, arranged substantially as described.

15 In testimony whereof I affix my signature in presence of two witnesses.

OSCAR F. GLIDDEN.
